UNITED STATES PATENT OFFICE

151,208

DESIGN FOR A HEAD FOR RAILROAD WATER HYDRANTS AND SIMILAR ARTICLES

Thomas E. Bart, Cincinnati, Ohio, assignor to
The Murdock Mfg. & Supply Co., Cincinnati,
Ohio, a corporation of Ohio

Application September 3, 1946, Serial No. 133,028

Term of patent 14 years

(Cl. D91—1)

To all whom it may concern:

Be it known that I, Thomas E. Bart, a citizen of the United States of America, residing at Cincinnati, in the county of Hamilton, State of Ohio, have invented a new, original, and ornamental Design for a Head for Railroad Water Hydrants and Similar Articles, of which the following is a specification, reference being had to the accompanying drawing forming part thereof.

Fig. 1 is a side elevational view of the head for railroad water hydrants and similar articles, showing my new design.

Fig. 2 is a front elevational view of the same.

Fig. 3 is a top plan view thereof.

Fig. 4 is a bottom view.

I claim:

The ornamental design for a head for railroad water hydrants and similar articles, as shown.

THOMAS E. BART.
